UNITED STATES PATENT OFFICE.

JOEL S. BORDEN, OF TOM'S BROOK, VIRGINIA.

WINDOW-SASH.

SPECIFICATION forming part of Letters Patent No. 601,547, dated March 29, 1898.

Application filed April 20, 1897. Serial No. 632,989. (No model.)

To all whom it may concern:

Be it known that I, JOEL S. BORDEN, a citizen of the United States, residing at Tom's Brook, in the county of Shenandoah and State 5 of Virginia, have invented certain new and useful Improvements in Window-Sashes; and I do hereby declare the following to be a full, clear, and exact description of the invention, such as will enable others skilled in the art to 10 which it appertains to make and use the same.

This invention has for its object to provide a window-sash of that class in which the parts thereof are constructed with a view of readily and conveniently inserting the panes 15 or glasses and thereby obviate the use of putty in holding the glasses in position. I provide means for holding the stile removably in position and also compensate for shrinkage, so that the parts may at all times be held 20 closely together to preclude the possibility of the entrance of rain or moisture, which tends to decay the sash.

In the following specification I have entered into a detail description of the invention, 25 reference being had to the accompanying drawings and to letters or numerals thereon which designate the different parts, and what I consider to be the novel features of construction are specifically set forth in the 30 claims.

In the drawings forming part of this specification, Figure 1 is a perspective view of a window-sash constructed in accordance with my invention. Fig. 2 is a transverse sectional view on a line X X of Fig. 1. Fig. 3 is a sectional view on a line Y Y of Fig. 1. Fig. 4 is an end view. Fig. 5 is a view with the removable rail disconnected.

Referring to the drawings by numerals, 1 1 40 designate the side rails of the window-sash, which are connected to each other at one end by a rail 2 by forming a mortise through the side rails to receive the tenons on the ends of the rail 2, the end rail being beveled to provide a neat joint at the corners by conforming 45 with the beveled inner edges of the side rails. Instead of providing these rails with the usual rabbet to receive the window-glasses and provide for applying putty they are 50 formed with longitudinal grooves or channels 3 a suitable distance from one edge. The side rails have formed in their inner

edges sockets or mortises 4, located opposite each other and adapted to provide for holding the stiles 5 in place, the said stiles having tenons formed at their ends which are brought into engagement with the mortises, there being sufficient play at the joints between the rails 1 1 and 2 to allow the stile to be sprung into place. It will be noted that 55 the ends of the stiles are beveled on opposite sides of the tenons to fit the beveled edges of the rails and are also formed with longitudinal channels or grooves 6, which communicate with the corresponding channels or grooves in 60 the side rails.

The ends of the side rails opposite their connection with the rail 2 are provided with projecting portions or tenons 7, which extend through mortises 8 in a removable rail 9, said 70 removable rail also having a longitudinal groove or channel 10 in its inner edge. The tenons at the ends of the side pieces do not extend entirely through the rail 9. This peculiar construction is provided to receive 75 turn-buttons 11, which are carried by the tenons, and when turned at an angle therewith engage the adjoining parts of the rail and hold it securely in engagement with the side rails. The tenons are also provided in 80 their outer ends with transverse recesses of a width equal to the turn-buttons, the said recesses being adapted to receive the turn-buttons when given a quarter-turn or when turned across the openings or mortises in the 85 connecting-rail. Thus after the tenons and turn-buttons have passed through the openings in the connecting-rail the buttons may be turned for preventing the connecting-rail from passing off the tenons, and after the 90 sash has been in use for a considerable time and shrinkage therein has taken place by tightening the screw around which the button turns the button may be depressed into the recesses in the end of the tenon, thus compensating for the shrinkage. 95

From the foregoing description, in connection with the accompanying drawings, the construction of my improved window-sash will be readily apparent, and it will be understood that in placing the glasses therein 100 the stiles and removable rail are disconnected from the side rails, after which the glass is slid between the said side rails into the groove

and the stile sprung into place, as hereinbefore described. The second glass is placed within the upper part of the frame and the top rail placed in position and held by the 5 turn-buttons, so as not to afford any projection beyond the outer surface of the rail. In case the frame is provided with four glasses the central stile is provided with sockets on opposite sides and the construction hereinbefore described carried out. I also anticipate providing the grooves with rubber or felt 10 cushions 12 to engage the edges of the glass and provide a tight joint that will aid in excluding weather.

15 By providing the rails and stiles with grooves instead of rabbets, in connection with the peculiar construction and arrangement hereinbefore described, I form a window-sash in which putty is dispensed with, and consequently 20 a more durable window-frame presented. In addition to this particular advantage it may be stated that the window-frame provides for quickly and conveniently replacing window-glasses, as it is only necessary to remove the top rail when an upper glass is to be replaced and both the upper rail and stile when a lower glass is to be inserted.

It will be observed that by reason of the employment 25 of the turn-buttons, which are mounted on screws, as shown, provision is made not only for removably holding the stile

in position, but also for tightening and adjusting the parts should they become shrunken. Furthermore, by reason of this disposition of 35 the securing means the appearance of the window is not marred and to an ordinary observer there is nothing to indicate that the sash is not of the ordinary construction.

Having thus described my invention, what 40 I claim as new, and desire to secure by Letters Patent, is—

1. A sash comprising stiles having end tenons, a connecting-rail having openings to receive said tenons, and turn-buttons on the 45 ends of the tenons approximately equal in size to the openings, adapted to pass therethrough, and to bear against the outer side of the rail when the latter is in place.

2. A sash comprising stiles having end tenons provided with recesses in their extremities, turn-buttons on the extremities of the tenons adapted to enter said recesses, screws around which the buttons turn, and a connecting-rail having openings to permit the 50 passage of the tenons and turn-buttons.

In testimony whereof I have signed this specification in the presence of two subscribing witnesses.

JOEL S. BORDEN.
